LAMP BASE OR SIMILAR ARTICLE

Filed May 22, 1935

FIG. 1.

FIG. 2.

Beth Weissman

INVENTOR

UNITED STATES PATENT OFFICE

96,287

DESIGN FOR A LAMP BASE OR SIMILAR ARTICLE

Beth Weissman, New York, N. Y.

Application May 22, 1935, Serial No. 56,962

Term of patent 3½ years

To all whom it may concern:

Be it known that I, Beth Weissman, a citizen of the United States of America, residing in New York city, in the Borough of Manhattan, county of New York, and State of New York, have invented a new, original, and ornamental Design for a Lamp Base or Similar Article, of which the following is a specification, reference being had to the accompanying drawing, forming part thereof, wherein,

I claim:

The ornamental design for a lamp base or similar article, substantially as shown.

BETH WEISSMAN.
